TEXTILE MILL SPINDLE

Jerome D. Gleitz, Pepper Pike Village, Ohio, assignor to
The Marquette Metal Products Company, Cleveland,
Ohio, a corporation

Application April 6, 1951, Serial No. 219,662

2 Claims. (Cl. 57—130)

The invention relates to textile mill spindles of the type designed to be mounted in rows on the rail or frame of a spinning or twisting machine in generally upright position and with their bobbin-supporting blades or live spindle parts driven by a common belt or band in friction contact with whorl portions of the blades.

The principal problem solved by subject invention (indicating the general object) is that of providing a more or less conventional steel spindle blade and whorl assembly with an enlarged diameter yet lightweight bobbin supporting portion adapted to be used successfully with "tube" type or style bobbins such as are usually made of paper or fibre stock and which are sometimes made of wood.

In the formation of composite spindle members of the sort outlined above and as shown by the embodiments illustrated herewith, it is essential that the portions of the assembly which directly support the bobbin be as nearly as possible concentric with the steel shaft by which the blade and whorl assemblies hence the bobbin and its load of yarn, are supported for turning. It is also essential that joints between the several parts wherever exposed for contact with the bobbin be closed and smooth, which is to say free from even slight recesses and abrupt shoulders such as would tend to collect and allow accumulation of dirt or lint. Additionally, it is necessary that the spindle as a whole be of as light weight or mass as possible so as not to add to the power required for turning the spindle and in order to minimize unbalanced weight in case the parts are not absolutely concentric. The present spindle blade and whorl assembly, regardless of the materials used to form it, meets the above requirements in a simple yet very practical manner thus indicating a further object of the invention.

In the drawing Figs. 1 and 2 are cross-sectional assembly views of two different forms of composite spindle blades. Fig. 1 shows the preferred construction in case the portion now generally called the barrel is of steel or more or less leavy metal and Fig. 2 shows the preferred arrangement in case the barrel is of light weight metal such as aluminum or magnesium. Fig. 3 is an approximately double scale fragmentary sectional detail view of the composite spindle blade construction hereof.

Referring first to the construction shown by Fig. 1, the hardened steel shaft 1 has, as usual, a smoothly finished shank portion 2 within the whorl 3 adapted for operative contact with a suitable bolster bearing, not shown (e. g. rollers), and a tapered lower shank end 4 for engagement with a footstep bearing. Those bearings are appropriately housed in a bolster (not shown) the particular construction of which is immaterial to the present subject.

The upper end of the whorl beyond the usual band-guiding upper flange 5 thereof has a more or less conventional acorn or hub portion 6 the upper end of which is slightly reduced in diameter as at 7 for abutment with the lower end of the barrel 10 as at the joint 11. The barrel 10 may be cylindrical or slightly tapered upwardly

2

and its upper end portion supports a bobbin drive head, top piece or tip 12 shown in the form of a plug having a shoulder 21 which forms one surface of a smooth joint 14. The tapered surface 13 of the tip engages the inner substantially mating surface at the upper end of the bobbin tube (not illustrated). The lower end of the bobbin tube extends downwardly beyond the joint 11 and is guided by a smooth portion 7a of the reduced diameter region 7 of the acorn and surrounds the acorn in loose-fitting relationship therewith. The barrel 10 provides a filler between the whorl of the steel spindle shaft and the bobbin-driving tip 12 of nearly the same upper and lower outer diameters as those of the acorn and tip respectively, so that the empty bobbin tube can be easily slipped over the spindle blade and, after loading, be easily doffed without encountering abrupt shoulders.

Assuming the barrel 10 is of steel or other relatively heavy metal, then its mass is reduced as a first operation on the somewhat oversize blank (not shown) from which 20 the barrel is formed by internally machining the top end of the blank as at 15 to such a depth as will leave only enough solid stock at the region generally designated 16 to assure a rigid support of the barrel on the top end portion or stub 17 of the shaft. The bore 15 is quite deep, most 25 of barrel being broken away as illustrated. The stub for the greater part of its length is cylindrical but it preferably has a reduced "pilot" end portion 17a with an end chamfer to facilitate assembly into the barrel bore 18.

In order to form the bore 18 which receives the blade 30 shaft stub 17 in strictly accurate alignment with bore 15 a suitable bushing (not shown) is inserted snugly into the bore 15 (slip fit) for guiding the tool which then forms the bore 18 completely through barrel portion 16. The bore 18 is made slightly smaller than the stub portion 17 which is shown as telescoped by barrel portion 16 so that 35 an extremely tight joint is secured between the stub and the barrel. Such joint may be effected simply by cold pressing the blade shaft and the barrel shank together in a well known manner, but preferably, in addition to press fitting, the barrel is heated considerably above the then 40 temperature of the shaft (or the shaft chilled for temperature differential), so that, in effect, both a press fitting and shrink fitting is obtained.

Assuming the tip or top piece 12 has been properly 45 formed with a cylindrical stub portion 20 and the smooth shoulder 21 defining one end of it, the stub portion is made of slightly larger diameter than the bore 15 and the top piece 12 is joined to the upper hollow end of the barrel 10 in exactly the same way as the shaft stub 17 is joined to the barrel. I find that it effects considerable 50 saving in time to press the shaft and cap piece into the heated barrel from its opposite ends simultaneously, that operation thus requiring only a single heating of the barrel 10 in order to obtain the combination shrink and 55 press fitting described above between the barrel 10 and the other two parts (top piece and shaft stub).

Further to reduce the weight of the blade assembly the top piece 12 is socketed at 31 as by drilling.

It is a difficult manner to obtain concentricity between 60 the shaft, barrel and tip and for practical purposes almost absolute concentricity must be achieved or the spindle blade assembly will not run true in its bolster bearings, particularly when the bobbin tube is loaded with yarn. By using a bushing as described above in the counter-boring 15 in order to locate the tool or tools which perform the axial boring 18, the shaft and barrel can be made truly concentric; and since the surfaces of top piece portions 13 and 20 are formed in a single operation, as on a screw machine, it is apparent that the tube supporting 65 or "seat" surface 13 for the bobbin will necessarily be concentric with the spindle blade.

At any step in the procedure and preferably after the

parts have been assembled as described, the footstep and bolster bearing portions 2 and 4 of the shaft are accurately located in a suitable fixture or chuck and a center drilling 23 is then formed at the extremity of the top piece 12 so as to be accurately co-axial with the shaft. Thereafter a considerable amount of stock is removed from the barrel blank (not shown) as on a lathe or grinder; and in so doing the joints 11 and 14 are made smoothly flush with the associated parts, leaving no gaps which could later receive lint or dirt.

In order to obtain a recess-free exterior surface at the joint 11, for example, either the lower end of the barrel 10 or the upper end of the acorn 6 is dished (made concave) so as to provide a slight cavity as at 25 inwardly from the perimetral regions of the joint 11. Thereby when the shaft stub is pressed into its bore 18, if the metal of the barrel is somewhat extruded beyond its originally formed (cut off) position the recess 25 will receive such extrusion or swelling of the barrel stock and the desired tight contact between the coating shoulders at the radially exposed portion of the joint 11 can be effected by pressure.

It should be mentioned that if the metal of the barrel 10 is of such nature that a wear proof bobbin-seat (e. g. like 13) can be formed directly on it, then the top piece (e. g. 12) need only be a plug for closing the counterbore 15 and to receive the center drilling 23.

Sometimes when the barrel 10 is heated prior to pressing the shaft stub 17 and top piece 20 into place as described, the subsequent cooling of the barrel results in opening of slight gaps at the joints 11 and 14, which then have to be re-closed by a second axial pressing of the parts toward each other (done cold). To prevent that from happening, I have found that by making for example the portion indicated 27 of the shaft stub slightly larger than the main diameter of the stub (best shown at 27' in Fig. 3) or, alternatively, by enlarging its diameter through ordinary knurling, such separation of abutting surfaces at the joint does not occur. The reason is that when the combined press and shrink fitting operation is completed and the parts have attained uniform temperature the pressure of the barrel metal against the shaft stub in region 27, Fig. 1, or 27' Fig. 3, is greater than at any other portion of the stub. During shrinkage of the barrel due to cooling should any relative travel or creeping between the barrel and stub occur, it will be in some region other than that indicated at 27 or 27' wherefore the joint will not open. The same treatment is preferably given the tip shank, for example local enlargement as by knurling of it in the region indicated at 28 which is nearest the joint 14.

When the knurling 27 and 28 is done by the usual method of rolling the overall diameter is preferably increased for example in the neighborhood of .005" or greater and the knurled region is spaced from the adjacent shoulders of the pieces to provide, in effect, undercuts 29 and 30 between the knurled regions and the shoulders. Thereby, particularly on the tip 12, the knurl-

ing does not interfere with the obtaining of a tight butt joint.

Exactly the same procedure as described above is preferably employed in the making of the blade assembly shown in Fig. 2 except that because the barrel 10a is of light weight metal, for example aluminum or magnesium, the upper drilling at 15a for the top piece 12a does not communicate with the lower drilling 18a which receives the shaft stub 17. Otherwise there is no important difference in the technique employed for forming the two illustrated constructions.

I claim:

1. A composite textile mill spindle blade and whorl assembly of the type adapted to support "tube" style bobbins, said assembly including a steel center shaft, and a metal barrel having an axial bore in its lower end portion tightly telescoping an upper stub portion of the shaft and, in effect, enlarging the diameter and axial extent of the upper end of the shaft, and a steel whorl operatively rigid with the shaft and having an acorn portion in tight abutment with an axial shoulder on the barrel, all around the barrel and of the same external diameter as the barrel, being flush therewith at the region of abutment; characterized in that substantial length portions of the stub portion functioning through the operative rigidity of the shaft with the whorl to maintain said abutment during use of the assembly, are fitted very tightly into the barrel bore, and further characterized in that the metal of the portion of the barrel which defines the lower end of the barrel is under greater radial stress, by being tighter on the stub portion, than along any other portion of the bore.

2. The construction according to claim 1 wherein the portion of the stub portion closely adjacent the lower end of the barrel is enlarged relative to portions of the stub portion upwardly therebeyond, and the bore in the barrel is of uniform diameter.
